UNITED STATES PATENT OFFICE

118,359

DESIGN FOR A COMBINED GLOBE AND PANEL FOR A LIGHTING FIXTURE

Albert L. Arenberg, Highland Park, Ill., assignor
to Patent License Corporation, Chicago, Ill., a
corporation of Illinois

Application April 17, 1939, Serial No. 84,343

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Combined Globe and Panel for a Lighting Fixture, of which the following is a specification, reference being had to the accompanying drawing, forming a part thereof.

In the drawing:

Fig. 1 is a face view of the combined globe and panel, showing my new design;

Fig. 2 is a side view of the same; and
Fig. 3 is an end view of the same.

The entire panel is translucent, and the surfaces which are shown stippled in the drawing are of a character to diffuse the light passing through such surfaces.

I claim:

The ornamental design for a combined globe and panel for a lighting fixture, substantially as shown and described.

ALBERT L. ARENBERG.
